UNITED STATES PATENT OFFICE.

GEORGE WILLIAM ALDRICH, OF ANTIGO, WISCONSIN.

WASHING-MACHINE CYLINDER.

1,254,187.

Specification of Letters Patent. Patented Jan. 22, 1918.

Application filed October 4, 1915. Serial No. 54,063.

To all whom it may concern:

Be it known that I, GEORGE WILLIAM ALDRICH, a citizen of the United States, residing at Antigo, in the county of Langlade 5 and the State of Wisconsin, have invented a new and useful Washing-Machine Cylinder to be Used for Dry-Cleaning, Washing, and Carpet-Cleaning Machines, of which the following is a specification.

10 My invention relates to new and useful improvements in cylinders for washing machines and the like adapted for disposition in an outer fluid container, whereby upon rotation of the cylinder, clothes placed thereon will be properly agitated for cleansing action by the fluid.

15 Washing machine cylinders of this nature embodied in commercial use are usually provided with a series of inwardly projecting 20 longitudinal peripheral ribs which are adapted to engage and lift the mass of clothes within the cylinder and then drop said mass of clothes to the bottom of the cylinder. Although this structure procures an efficient cleansing action, it is open to 25 serious objection in that the clothes are subjected to severe strain during operation of the cylinder by abutment of the ribs and by dropping on the ribs at the relatively high 30 speed at which the cylinder must rotate. Thus the life of the clothes is materially shortened due to breakage of the fibers thereof, and a considerable amount of lint results.

It is primarily the object of my invention 35 to provide an arrangement within the cylinder whereby the clothes may be properly manipulated to procure an efficient cleansing action, in such manner that the clothes are not subjected to breaking strains, and it is 40 more specifically the object of my invention to procure a manipulation of the clothes similar to hand washing, by the provision of successive squeezing and rubbing actuations of the clothes.

45 A further important object of the invention resides in the provision of an arrangement whereby upon alternately opposite rotations of the cylinder, the clothes may be caused to travel from end to end thereof and 50 whereby the clothes are subjected to a rubbing actuation at either end of the cylinder when massed there adjacent.

55 A still further object resides in the provision of means for introducing cleansing fluid into the cylinder from the outer drum in such manner as to serve as a lubricant for

the clothes when being subjected to a rubbing action.

A still further object resides in the provision of a simple cylinder of the present 60 nature, which may be constructed entirely of metal in a manner permitting a most ready assembly, and in this connection it is more specifically an object to utilize the formation of inwardly extending ribs of the 65 cylinder to provide grooves in the outer face of the cylinder for agitating cleansing fluid thereof.

With the above and other objects and advantages in view, the invention resides more 70 particularly in the novel combination, formation and arrangement of parts hereinafter described and pointed out in the appended claim.

In the drawings:

75 Figure 1 is a perspective view of a washing machine cylinder constructed in accordance with the present invention.

Figs. 2, 3 and 4 are diagrammatic elevational views of the cylinder, partly in sections, and showing the longitudinal travel 80 of the mass of clothes procured by successively reversed rotative movements of the cylinder.

Figs. 5, 6 and 7 are partly diagrammatic 85 transverse sectional views through the cylinder, showing the successive squeezing, dropping and rubbing actuations of the mass of clothes upon the rotation of the cylinder.

Fig. 8 is an enlarged transverse sectional 90 view through the cylinder.

Fig. 9 is an elevational view of the end rubbing plate of the cylinder.

Fig. 10 is a sectional view through said 95 plate on the line 10—10 of Fig. 9.

Fig. 11 is an elevational view of one of the end head plates of the cylinder.

Fig. 12 is a detail elevational view of the door of the cylinder.

Referring now more particularly to the 100 accompanying drawings, the cylinder comprises a series of V-shaped rubbing rib staves 20 between which are disposed spacing staves 21 riveted to the inner face of laterally turned flange portions at the outer edges of 105 the rubbing rib staves 20. The staves 20 and 21 form the major portion of the periphery of the cylinder, and secured to one of the endmost series of rubbing rib staves 20 is one edge of the relatively wide spacing 110 rib stave 23 which has its other edge secured to one laterally turned edge of a lifting rib

stave 24. A door 25 is hingedly connected with the other edge of the lifting rib stave 24 and is adapted to close the space between said lifting rib stave and the adjacent rubbing rib stave 20, this space being substantially equal in width to the width of the spacing stave 23. The height of the lifting rib stave 24 is, as shown in the drawings, four times the height of the rubbing stave 20, and may be of a much greater relative height. Also the rubbing rib staves 20 may be positioned relatively much closer together. The rib staves 20 and 24 extend at their ends a slight distance beyond the ends 15 of the spacing staves 21 and 23 and the door 25, and end rubbing plates 26 are provided for the cylinder which are adapted at their peripheral portions to abut the ends of the spacing staves and door and which are provided in said peripheral portions with slots 27 and 28 for receiving the ends of the rib staves 20 and 24 respectively. Inwardly struck on the plates 26 are radial series of rubbing ribs 29, said ribs being preferably 25 grouped adjacent the rubbing ribs.

For holding the staves and end plates in assembled relation, end head plates 30 are provided each including a hub portion carrying an outwardly projecting pintle 31, and 30 radial arms connected at their outer portions to form the periphery of the plate, said periphery being provided with an in-turned annular flange 32 embracing the staves and bolted thereto. For bracing the 35 staves, bars 33 are disposed in the eight portions of the rib staves and are extended through the peripheral portions of the head plates 30 and secured by bolts 34. These bars are of any desired nature and may 40 comprise pipe lengths plugged at their ends.

The door 24 is secured in closed position by spring urged end locking bolts 35 carried thereby and adapted to engage in recesses 36 in the peripheral portions of the 45 end rubbing plates 26. The door is also provided with a central spring urged locking bar 37 and all of these locking bars are preferably connected in a suitable conventional manner for simultaneous operation.

50 To permit free passage of cleansing fluid through the cylinder, the spacing staves and the door are provided with openings 38 of a maximum number consistent with sufficient strength of the staves and the door. The 55 staves and the door are also provided with outwardly struck cupped portions 39 which are also formed with said openings.

As is shown more particularly in Figs. 1 and 12, the staves and consequently the ribs 60 formed by alternate staves are slightly inclined with respect to the axis of the cylinder.

Taking up now the operation of the cylinder, it is noted that when the cylinder is operatively disposed in an outer drum, the 65 plane of the cleansing fluid would extend

thereinto a distance somewhat less than the height of one of the rubbing ribs. The charge of clothes disposed in the cylinder would be of the relative bulk indicated in Figs. 2 to 7, thus referring more particularly to Figs. 5 to 7 upon rotation of the cylinder, and engagement of the lifting rib stave 24 with the clothing, said clothing would be squeezed in the space at one side of the lifting rib and simultaneously lifted. Upon reaching the position of Fig. 6 the clothes would then drop to the bottom of the cylinder. In view however, of the multiplicity of the rubbing rib staves 20 and their relatively small height, the force of fall of the clothes would be distributed in such manner as not to impart an excessive strain to the fibers thereof. Continued rotation of the cylinder would cause a rubbing action of the clothes by the rubbing rib 85 staves 20, similar to the manual action procured in connection with a washboard. In this rubbing movement the clothes gradually settle upon the rubbing stave until they reach a final position at the lifting side of 90 the rib stave 24 and seat within the relatively great space between said lifting rib and the adjacent rubbing rib.

The cycle described is then repeated and the clothes are thus subjected to successive 95 squeezing and lifting, dropping and rubbing actuations, thus procuring an operation similar to the manual operation of washing by hand, and wherein the clothes are subjected to comparatively slight strain to consequently materially lengthen the life of the 100 clothes.

As shown more particularly in Figs. 2 to 4, upon continued rotation of the cylinder the clothes gradually travel toward and become massed at one end of the cylinder due to the inclination of the ribs, and when massed at one end of the cylinder the clothes are subjected to a considerable rubbing action by the rubbing ribs of the end plates 26. The cylinder is adapted to have imparted to 105 it successive series of rotations in alternately opposite directions and thus the clothes travel alternately from end to end thereof during the entire cleansing operation.

By the provision of the cup shaped portions 39 on the periphery of the cylinder, cleansing fluid is scooped into the cylinder upon passing of said portions therethrough and thus a positive fluid lubrication for the clothes is insured at the points most needed during the rubbing engagement. When the cylinder is relatively small, corrugations may be substituted for the cupped portions to procure the same scooping action.

115 Various washing cylinders have been heretofore provided including rubbing ribs on the periphery but without the provision of a lifting and squeezing means, the cleansing fluid is not properly distributed through the 120 125 130

mass of clothes, nor is the mass of clothes sufficiently agitated to present all portions thereof to the rubbing action. I am aware that means have been heretofore provided 5 for turning clothes during said rubbing actuation, but a squeezing or wringing action is also essential to procure passage of the cleansing fluid therethrough.

I am also aware that cylinders have been 10 heretofore provided with lifting and squeezing ribs, but such cylinders do not contemplate the provision of a rubbing means and thus must depend upon an exceedingly rapid rotation of the cylinder to procure a sufficient agitation of the clothes and this rapid 15 rotation is fatal to the proper length of life to the clothes. Experience has demonstrated that such machines must be rotated at an approximate speed of thirty-three revolutions 20 per minute, while my machine is most efficient at an approximate speed of sixteen revolutions per minute, thus in addition to relieving the clothes from the rapid impact of the ribs my arrangement also relieves the 25 clothes from falling upon the projected surface of the lifting rib, since I employ only one lifting rib and the rubbing ribs are of such multiplicity and size as to distribute the force of fall of the clothes.

The essential feature of my invention re- 30 sides in the provision of a washing cylinder provided with a series of rubbing ribs and with a single lifting and squeezing rib, and while I have shown my invention associated particularly with the cylinder of a fluid 35 washing machine, it is obvious that it is adapted for use in other cleansing devices, and it is further obvious that various changes and modifications of structure to meet differing conditions of use may be re- 40 sorted to without departing in any manner from the spirit of the invention as interpreted by the appended claim.

I claim:

A cleaning cylinder adapted for horizontal disposition and comprising a peripheral wall formed of alternately arranged V-shaped staves and spacing staves, and end wall members having rubbing surfaces thereon and closing the ends of the cylinder, said 45 V-shaped staves being inclined with respect to the axis of the cylinder, substantially as described.

GEORGE WILLIAM ALDRICH.
